J. A. DUNPHY.

RUBBER SOLED SHOE AND METHOD OF MAKING THE SAME.
APPLICATION FILED JAN. 24, 1916.

1,316,562.

Patented Sept. 23, 1919.

INVENTOR

James A. Dunphy

UNITED STATES PATENT OFFICE.

JAMES A. DUNPHY, OF GROTON, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

RUBBER-SOLED SHOE AND METHOD OF MAKING THE SAME.

1,316,562.

Specification of Letters Patent. Patented Sept. 23, 1919.

Application filed January 24, 1918. Serial No. 73,915.

To all whom it may concern:

Be it known that I, JAMES A. DUNPHY, a citizen of the United States, residing at Groton, in the county of Middlesex and 5 State of Massachusetts, have invented certain Improvements in Rubber-Soled Shoes and Methods of Making the Same, of which the following description, in connection with the accompanying drawings, is a specification, like reference characters on the 10 drawings indicating like parts in the several figures.

This invention relates to the manufacture of rubber soled shoes and more particularly 15 to a novel method of making rubber soled shoes of the type having a canvas or similar textile upper and a vulcanizable rubber sole bottom and to a novel rubber soled shoe of this type. These types of rubber 20 soled shoes are generally known as "sneakers" and according to the present commercial method of manufacture the canvas upper and the various rubber bottoming materials are secured together by 25 vulcanization. Although these sneakers supply the present demand for an inexpensive shoe adapted for summer wear they are unsatisfactory because of their weight and clumsy appearance and the rubber 30 composition insoles sweat the feet. Furthermore the attachment of the rubber sole to the canvas upper is entirely dependent upon the durability of the vulcanization which is often faulty so that the shoe gives unsatisfactory service. Also the "foxing" extending 35 along the side of the upper adjacent the sole is objectionable as it adds appreciably to the cost of the shoe and gives a characteristic "sneaker appearance" to the shoe.

40 The present invention has for its general object to improve the manufacture of rubber soled shoes of this type whereby the shoes produced is a much more comfortable and more serviceable shoe than the present 45 commercial rubber soled shoe and has a neater and more stylish appearance since the necessity of employing a foxing along the side of the shoe is eliminated.

The invention will now be described with 50 particular reference to the accompanying drawing, and the invention will be pointed out in the appended claims.

The drawing illustrates, in perspective, a rubber soled shoe made in accordance with

the present invention, certain portions of 55 the shoe being broken away to show its construction more clearly.

In carrying out the method of making rubber soled shoes of this invention according to one manner in which it has been successfully practised the upper 2 of canvas or similar textile material is first assembled on the last together with an insole 4 of fibrous materials. Preferably the insole is composed of a vegetable fiber in order that it 60 may withstand uninjured the high degree of heat necessary to vulcanize the outsole to the shoe. It has been found that satisfactory results can be obtained by the use of "sulfite" fiberboard.

The shoe upper is now lasted over on to the insole entirely around the shoe and temporarily secured in tensioned position by cement applied to the inner surface of the lower marginal portion 6 of the upper either previous to assembling the upper on the last or progressively as the shoe is lasted.

The lasted shoe is now ready to receive the middle or intermediate sole 8 which may consist of a sheet of strong textile material preferably impregnated with rubber so as to provide on its upper side an efficient surface to which an outsole can be later vulcanized. The marginal portion of the sole 8 completely around its edge is folded or turned back on to the body portion, preferably on the underside of the sole, and the width of the fold may be sufficient to allow the flap 10 to extend beyond the inner edge of the overlasted portion of the upper when applied to the shoe, as illustrated. Also the outer folded edge 12 should project outwardly a short distance beyond the edge of the upper completely around the shoe. By folding the marginal portion of the middle 85 sole as described a relatively stiff and firm projecting portion is provided to which an outsole may be securely anchored by vulcanization and a raw edge of the fabric middle sole is avoided. The under surface of the middle sole 8, or it may be the opposed bottom face of the lasted shoe, is then thoroughly coated with a suitable rubber cement and the middle sole 8 is applied and caused to adhere to the lasted shoe bottom.

100 At this stage of the manufacture of the shoe, the last is withdrawn from the shoe to enable the insole, upper and middle sole to be

united by stitches 14. The sewing operation may be performed on any of the well known straight needle sewing machines such for example as disclosed in United States 5 Patent No. 1,050,568 granted on application of R. Scott, it being preferable however to use a thread which is free from wax or other fatty elements since such materials on a wax thread would be detrimental to 10 the proper vulcanization of the outsole to the middle during the latter vulcanizing operation. The stitches 14 pass through the insole, the overlasted edge 6 of the upper and the two plies of middle sole material 8, 15 as shown, and the seam preferably extends completely around the shoe, thus permanently uniting the several parts of the shoe much more strongly and with greater facility than they can be united by vulcanization.

20 The last is then reinserted in the shoe, or a second last or easily inserted form may be used, and an outsole 16 which is died out from a sheet of calendered rubber or rubber composition is next applied to the shoe 25 bottom. This outsole is shaped to cover the entire middle sole 8 and while it is plastic its outer edge is preferably molded by suitable means over the outer edge of the middle 30 sole and on to its projecting upper surface, as indicated at 18 in the drawing, but the outsole is not carried up on to the upper 2 of the shoe. If the shoe is to have a heel 35 an additional lift 22 of rubber compound may be applied to the heel end of the outsole and the entire bottom of the shoe conformed to the contour of the bottom of the last by rolling pressure.

40 The shoe is now placed in a suitable vulcanizing apparatus where it remains for a sufficient length of time for the outsole and heel of rubber compound to be thoroughly cured and the outsole to become properly vulcanized to the middle sole, the rubberized 45 surface of the middle sole materially assisting its vulcanization.

50 It will be noted that the above described method of making rubber soled shoes eliminates several of the more exacting operations which are practised in the manufacture of sneakers and that the employment of the fibrous insole and the textile middle sole produces a shoe which is not only superior to the sneaker but which costs considerably less, and the fibrous innersole and textile middle sole can be handled throughout the factory with greater facility than the calendered rubber materials which are essential under the practice of manufacturing 55 sneakers.

60 The rubber soled shoes produced by the method above described are considerably lighter in weight and far more comfortable than the sneaker since only the outsole is of 65 rubber compound. Also because the rubber

compound is effectively insulated from the foot by the textile middle sole and the fibrous or leather-board insole the objectionable drawing and sweating action caused by a rubber compound insole is eliminated. Furthermore the shoe produced by the present invention presents a neat and stylish appearance clearly distinguished from the commercial sneaker since the usual foxing is wholly absent, the sole has a distinct edge face and 75 the shoe has a crease similar to the welt or rand crease between the sole and the upper of a leather shoe.

70 Having described my invention I claim as new and desire to secure by Letters Patent 80 of the United States:—

1. That improvement in methods of making rubber soled shoes which consists in assembling on a last an upper and an insole of fibrous material which will withstand 85 without injury the heat of vulcanization, lasting the upper over on to the insole and temporarily securing it under tension to the insole, applying a rubber impregnated fabric intermediate sole shaped to cover the entire 90 lasted shoe bottom and extend beyond the upper and turning its marginal portion back upon itself to provide a firm extension edge for said sole, permanently securing said intermediate sole to the upper and the insole 95 by stitches passing through the folded portion of the sole, the overlasted portion of the upper and the insole, applying an outsole of vulcanizable material to the intermediate sole, and uniting the outsole to the intermediate sole by vulcanization.

100 2. That improvement in methods of making rubber soled shoes which consists in assembling on a last an upper and an insole of fibrous material which will withstand without injury the heat of vulcanization, lasting the upper over on to the insole and temporarily securing it under tension to the insole, applying a rubber impregnated fabric intermediate sole shaped to cover the entire 105 lasted shoe bottom and extend beyond the upper and folding its marginal edge back upon itself so as to present a firm and finished extending sole edge, permanently securing the sole to the upper and the insole 110 by stitches passing through the margin of the intermediate sole, the overlasted upper and the insole, applying an outsole of vulcanizable material to the bottom surface of the intermediate sole, shaping the outsole 115 material to cover the extending edge of said intermediate sole, and uniting the outsole to the intermediate sole by vulcanization.

120 3. A rubber soled shoe comprising an insole of fibrous material which will withstand 125 without injury the heat of vulcanization, an upper lasted over on to the insole, a fibrous intermediate sole covering the lasted shoe bottom and having its marginal edge folded back upon itself, a seam of stitches passing 130

through the folded portion of the intermediate sole, the overlasted upper and the insole, and an outsole of rubber compound united to the intermediate sole by vulcanization.

4. A rubber soled shoe comprising an insole capable of withstanding the heat of vulcanization, a fabric upper lasted over the insole, an intermediate sole McKay sewed 10 through the upper to the insole and having a reinforced marginal portion extending be-

yond the upper to present a crease similar in appearance to a welt or rand crease, and a rubber composition outsole molded on to the shoe bottom and over on to the exposed 15 upper surface of the extending portion of the intermediate sole to present an all-rubber sole extension and vulcanized to the intermediate sole.

In testimony whereof I have signed my 20 name to this specification.

JAMES A. DUNPHY.
